B. FOTHERINGHAM

BURGLAR ALARM

Filed July 22, 1925

Inventor:
Bruce Fotheringham
by Hayard and Miller
Attorneys.

UNITED STATES PATENT OFFICE.

BRUCE FOTHERINGHAM, OF ONTARIO, CALIFORNIA.

BURGLAR ALARM.

Application filed July 22, 1925. Serial No. 45,226.

To all whom it may concern:

Be it known that I, BRUCE FOTHERINGHAM, a citizen of the United States, residing at Ontario, in the county of San Bernardino and State of California, have invented new and useful Improvements in Burglar Alarms, of which the following is a specification.

My invention is a burglar alarm of the explosive type adapted to discharge a blank cartridge on the opening of a door, gate or the like. My invention is particularly adapted for use in a farm enclosure for stock or the like or for a poultry house in which an authorized person may set the gun from the inside of the enclosure or the poultry house, close the gate or door and release the latch of the gun so that it will be set to explode on the opening of the gate or the door.

My invention in its various details comprises a gun having a fixed cartridge holder and a heavy spring actuated hammer which is maintained in an elevated position with the springs tensioned by a spring pressed arm, the latter being movable on the opening of the door to release the hammer. I also provide a latch so that the hammer may be held in a safety position after loading the gun on the inside of the yard or poultry house and the latch may be released from the outside to allow the hammer to come into engagement with a pivoted arm or trigger.

My invention will be more readily understood from the following description and drawings in which;

Figure 1 is an elevation of my burglar alarm gun showing the hammer elevated in its latched position in what may be considered a safety lock.

Fig. 2 is an elevation similar to Fig. 1, showing the hammer engaging the swiveling trigger arm and in a position for exploding the cartridge on the opening of the gate or door.

Fig. 3 is a view similar to Figs. 1 and 2, showing the hammer dropped, exploding the cartridge on the opening of the gate or door.

Fig. 4 is a horizontal cross section on the line 4—4 of Fig. 2.

Fig. 5 is a horizontal section on the line 5—5 of Fig. 3.

Fig. 6 is a vertical section on the line 55 6—6 of Fig. 2 in the direction of the arrows.

In the drawings 1 indicates a fixed part of a fence or the interior wall of a building such as a post or a door frame of a building and 2 designates a fence gate or a building door being hinged by the hinges 3 to the post or door frame. My alarm gun signal is adapted to be actuated on the unauthorized opening of the gate or door. 65

The signal comprises a bracket 4 having a gun barrel 5 formed of a section of tubing of such internal diameter as to hold the cartridge shell 6 and engage the rim 7 thereof. The bracket is secured to the post in any suitable manner and forms a stationary mounting for the gun barrel or tube. The hammer 8 consists of a heavy bar of metal 9 having a cylindrical bore 10 at its lower end adapted to slide on the outside of the barrel 5 and having a projection 11 to engage the explosive cap of the usual cartridge. The hammer is provided with a latch slot 12 in one side for a purpose to be hereafter described. The upper end of the hammer bar has a stem 13 preferably of reduced diameter, with an elongated notch 14, cut in one side. This notch has a squared shoulder 15, an inclined shoulder 16, and an inclined tip 17. 85

A yoke 18 extends across the hammer bar and is connected thereto by means of a slot 19 in the yoke engaging around a rivet 20 secured to the hammer bar. A pair of tension springs 21 are secured to the yoke and at their lower ends are fastened by hooks 22 to the bracket 4. These springs function to draw the hammer bar downwardly with considerable force to explode the cartridge so that the action is practically independent of the drop of the hammer by gravity after being tripped as hereafter explained. 95

The trigger arm 23 consists of a metal rod pivotally connected to the upper end of the bracket 4 by means of a swivel pin 24. The outer end 25 of the trigger arm is adapted to bear against the door 2. A tension spring 26 is positioned between the arm and the post 1 to hold the arm tightly pressed against the door. The arm engages in the notch 14 engaging the shoulder 15 to hold the hammer in set position. 105

The latch which also forms a safety device is designated generally by the numeral 27 and comprises a latch bar 28 sliding in a socket 29 and be operated by a key 30 5 engaging the latch bolt to retract it or to project it into engagement with the latch slot 12. The key is removable from the latch at the outside and a knob 31 is provided on the inside so as to operate the 10 latch. The latch shown is of a type which remains in the position in which it is moved by the key or the knob.

The manner of loading the gun is as follows:

- 15 The yoke 18 is lifted off the rivet 20 so that the hammer may be completely removed from the barrel 5. A cartridge is then inserted and the hammer replaced, the yoke being secured in its normal position.
- 20 The hammer will then be raised until the latch bar 28 is opposite the latch slot 12 when the latch bar is moved into engagement therewith through the medium of the knob 31. This setting of the gun in the safety 25 latch position is done by an authorized party from the interior of the building or the enclosed yard.

When the gate is swung closed by the operator passing out therethrough, the trigger 30 arm swings from the position shown in Fig. 5 to that of Fig. 4 so that it fits within the slot or notch 14 in the stem 13 of the hammer bar. When the operator is on the outside of the building or the enclosure, he operates the 35 latch bar 28 by means of the key 30 to withdraw the bar from the slot 12 and thereby sets the gun in operative position.

The discharge of the gun is caused by the 40 opening of the gate in which action a trigger arm 23 is pressed outwardly from the position shown in Fig. 4 to that of Fig. 5 and so releases the engagement of the arm and the shoulder 15 of the stem, allowing the hammer to drop and explode the cartridge.

45 As above described the tension springs 21 draw the hammer downwardly with considerable force, thereby making the device independent of gravity.

50 The gun and hammer with the other detail parts of the mechanism may be placed in different positions if desired and may be arranged to discharge vertically as the firing action is mainly caused by the springs.

55 After the operator has set the gun to discharge for instance in the evening, he may set it in the safety position, for instance in the morning by utilizing the key to throw the latch bar into engagement with the latch slot 12 and thus lock the hammer bar against firing. He may then open the gate or door and pass in and out freely. With the construction shown it is not necessary to unload the gun, as this is a simple matter it may be 60 quickly accomplished or if desired the hammer may be manually lowered into the posi-

tion of Fig. 3 or the device left locked until it is desired to reset the gun.

My burglar alarm may be considerably modified to suit special requirements, different ways of mounting and so forth. Other 70 types of latches may be used or they may be discarded if a person merely wants a simple device, in which case the gun could be set from the outside of the yard or building by the operator passing a loop wire through an 75 aperture 32 in the gate above the hammer, the loop being designed to engage either the rivet 20 or the shoulder 15.

Having described my invention, what I claim is:

1. A burglar alarm comprising in combination a barrel adapted to hold and retain a cartridge, a hammer bar having a cylindrical bore, said bore being adapted to slide over the barrel and having a notch at its upper end, a trigger arm adapted to engage in the notch, said trigger arm being adapted to swivel to release the hammer bar and allow the hammer to drop to strike and explode the cartridge.

2. A burglar alarm comprising in combination a bracket adapted to be secured to a gate post, a tubular barrel secured thereto adapted to hold a cartridge with its rim on the upper end of the barrel, a hammer bar having a cylindrical bore in its lower end, said bore being slidable over the barrel, an upwardly extending stem connected to the hammer bar and having a notch therein with a squared shoulder, a trigger arm pivoted to the bracket to swing horizontally, a spring to draw the trigger arm towards the post, said trigger arm having its outer end shaped and positioned to engage a gate and to engage the said shoulder whereby on opening 95 the gate the trigger arm is swivelled out of engagement with the shoulder to allow the hammer to drop and explode the cartridge.

3. A burglar alarm comprising in combination a bracket adapted to be secured to a gate post, a tubular barrel secured thereto, adapted to hold a cartridge with its rim on the upper end of the barrel, a hammer bar having a cylindrical bore at its lower end, said bore being slidable over the barrel, an upwardly extending stem connected to the hammer bar, having a notch therein, a trigger arm pivoted to the bracket to swing horizontally and to engage the said notch, the hammer bar being provided with a latch slot, a slidable latch adapted to be attached to the post to engage said latch slot, a rivet secured to the hammer bar, a detachable yoke on the latch bar engaging the rivet, and tension springs between the yoke and the lower portion of the bracket.

In testimony whereof I have signed my name to this specification.
